UNITED STATES PATENT OFFICE

RODRIGO F. DURÁN, OF BARRANQUILLA, COLOMBIA

COMBINED MESSAGE BLANK AND ENVELOPE

Application filed March 16, 1931. Serial No. 522,997.

This invention relates to improvements in message blanks such as used by telegraph and cable companies of such form that the single blank provides the message space and the envelope.

One of the objects of this invention is the provision of an article of this type constructed so that the message may be addressed and typed on the blank in duplicate.

Another object of the invention is the provision of an article of this type made so that the duplicate may be detached from the original and the original so folded that the message is sealed against inspection and the address is exposed so that the message may be properly delivered.

A still further object is the provision in a construction of this type of tear strips arranged so that when the message is sealed it cannot be exposed to view until the sealing strip is torn off.

A further object of the invention is the provision of several forms of seals, one of which comprises a receipt which may be detached from the article when it is delivered and returned to the originating office.

These and other objects as will appear from the following disclosure are secured by means of this invention.

This invention resides substantially in the combination, construction, arrangement and relative location of parts all as will be set forth in greater detail below.

Referring to the drawing—

Figure 1 is a plan view of the combined message blank in duplicate and envelope;

Fig. 2 shows the blank partially folded with the duplicate removed;

Fig. 3 is a view of the blank as folded in Fig. 2 from the other side;

Fig. 4 shows the message blank folded over and sealed to provide the envelope;

Fig. 5 is a plan view of the receipt form of seal;

Figs. 6 and 7 are plan and edge views of the message blanks with the receipt applied to seal the message; and

Fig. 8 is a view with the seal of either type removed and the blank ready for opening.

Referring to the drawing the complete

combined message blank in duplicate which may be folded to form the envelope as shown in Fig. 1 comprises a body portion made up of the parts 1 and 2 which are integral and which may be easily detached along the perforated line 3. The lines 4, 15 and 16 define the main body of the message blank. The perforated line 5 together with the perforated lines 13 and 14 permit of removal of the central portion of the blank to produce its final form. Lines 6 and 7 provide the spaces A and B. The space A is provided for advertising instructions, rates, etc. The space B is provided in which may be written the telegraph station or office at which the message is received. Lines 9 and 10 together with line 7 provide the spaces C and D in which further advertising matter and instructions may be printed. Line 8 is a perforated line. Line 11 provides the space E in which the addressee data is placed. Line 12 is a perforated line. Space F is the space for the message. The underface of the portion 1 of the blank provides a surface for the duplicate data and, of course, a sheet of carbon paper is placed between them when the data is written or typed on the original.

After the receiving station data, the address and the message have been written or typed in the spaces B, E and F the portion 1 is detached from the portion 2 along the perforated line 3 and retained by the telegraph or cable company as a record. The original is then folded along the perforated line 12 backwardly so as to lie parallel with the portions E and C and D. The portions A and B are then folded back over the portion F along the line 8. The blank then looks from one side as shown in Fig. 2 and from the other side in Fig. 3. The small portion of the blank terminating on the line 3 of Fig. 3 is, of course, folded down flat. The blank is then folded transversely of its center for the form in Fig. 4 so that the space C and a portion of the space E provide the face of the envelope and the address will appear thereon, it having been written to the left of the space E. The blank is then sealed by means of clips, for example, as at 20 in Fig. 4. The blank may also be sealed

by means of a strip of paper such as shown in Fig. 5 which comprises the portions 22 and 30 to be folded along the line 23 and a portion 21 united to the other portion by the 5 perforated line 23. The underfaces of the portions 22 and 30 are gummed so that they may be moistened and folded over the left-hand edges of the blank when in the form of Fig. 4 as indicated in Figs. 6 and 7. As 10 shown in Fig. 6 the perforated line 24 is a little to the left of the perforated line 14. When the message is delivered the receiver signs the receipt and the portion 21 is detached by the messenger and returned for 15 filing. The receiver may then open the message by tearing off the left-hand end along the perforated line 14, Fig. 6, and in a similar manner the lefthand end of the envelope may be torn off when the fastening clips 20 20 as shown in Fig. 4 are used. The result is shown in Fig. 4. The blank may now be unfolded. It will then have the appearance of the portion in Fig. 1 between perforated lines 13, 3 and 14. If desired this 25 portion may then be broken up into the portions comprising the spaces A and B, C, D and E and F. By folding in the manner disclosed it is apparent that the message in the space F is folded but within the blank so 30 as not to be exposed until the seals are broken.

It is, of course, apparent that this invention may be varied by those skilled in the art without departure therefrom and, hence, I 35 do not desire to be strictly limited to the disclosure as given in an illustrative sense but rather to the scope of the appended claims.

What I seek to secure by United States 40 Letters Patent is:

- 33 1. A combined message blank and envelope comprising a sheet having defined spaces for address and message data, said blank being foldable to enclose the message, 45 means for sealing the folded blank along the free edges comprising a sheet in the form of a receipt glued over the free edges.
- 33 2. A combined message blank and envelope comprising a sheet having defined 50 spaces for address and message data, said blank being foldable to enclose the message, means for sealing the folded blank along the free edges comprising a sheet in the form of a receipt glued over the free edges, 55 said receipt sheet having a free portion attached to the glued portion along a perforated line, the message blank having perforated lines adjacent the sealed edges and displaced from the perforated line on the re- 60 ceipt sheet.

In testimony whereof I have hereunto set my hand on this fifth day of February A.D., 1931.

RODRIGO F. DURÁN.
